By his Attorney,
Kelson W. Howard

UNITED STATES PATENT OFFICE

HENRY B. GORMAN, OF LYNCHBURG, VIRGINIA, ASSIGNOR TO UNITED SHOE MANUFACTURING CORPORATION, OF PATERSON, NEW JERSEY, A CORPORATION OF NEW JERSEY

INSOLE

Application filed May 17, 1927. Serial No. 192,037.

This invention relates to insoles and is illustrated with reference to insoles for use in the manufacture of shoes in which an upper is lasted over an insole, and an outsole, 5 the upper and the insole are secured together by through-and-through fastenings.

Objects of the invention are to provide an improved insole to which the upper may be attached by metallic fastenings without any 10 liability of the fastenings appearing on the inner face of the insole, to provide an insole the outer surface of which, after attachment of the upper, will be smooth and substantially unbroken, as well as to provide an insole 15 which will be convenient to use and cheap to manufacture.

As herein illustrated, the invention provides an insole comprising two layers of material which are coextensive with the last bottom, the outer layer having cuts extending through it and providing tabs which may be readily raised so that a clinching tool may be placed beneath the raised portions to clinch against the lower face of the outer layer a 25 fastening driven through the upper and the outer layer. In one illustrated form of the invention, such tabs are provided at frequent intervals along the margin of the outer layer of the sole, the attached ends of the tabs being 30 spaced from the edge of the sole and the free ends of the tabs being directed inwardly. Each of the tabs is therefore adapted to receive a fastening driven through the upper and the tab, which fastening may be clinched 35 on the inner face of the tab by a clinching tool placed beneath it. After the upper is lasted, the tabs may be forced into the recesses from 40 which they were cut so that the outer surface of the insole will be smooth and substantially unbroken.

In lasting the toe and heel ends of shoes, the upper materials are frequently lasted over the bottom of the insole and secured by tacks which are driven through the upper and the 45 insole and clinched by iron plates on the ends of the last. Accordingly, the lasting tabs, as illustrated, do not extend beyond the tip line and breast line. It is to be understood, however, that the tabs may be continued toward the ends of the insole so that the ends

of the shoe may be lasted in the same way as the sides.

Other features of the invention will appear more fully from the following description when read in connection with the accompanying drawing and will be pointed out in the claims.

In the drawing,

Fig. 1 is a perspective view of a shoe having an insole embodying the present invention;

Fig. 2 is a detail view of the insole showing the lasting tabs;

Fig. 3 is a perspective view of an insole showing a modified form of the invention;

Fig. 4 is a transverse section of a shoe having an insole of the form shown in Fig. 3.

Insoles embodying the present invention are preferably of sheet-material, such as buckram, canvas or split leather, the illustrated material being frictioned canvas of such weight that two thicknesses of it will provide proper strength and flexibility for an insole for the type of shoe being made. Thus the insole illustrated in Fig. 1 consists 75 of two adhesively connected pieces of sole-shaped frictioned canvas 10 and 12, one overlying the other. An advantage of employing frictioned canvas is that the two layers comprising the insole may be caused to adhere 80 simply by being pressed together. It should be understood, however, that for either or both of the layers 10 and 12, material other than frictioned canvas may be substituted, and other means of securing the insole layers 85 together may be employed. Conveniently, although not necessarily, the pieces 10 and 12 are die cut or otherwise cut to insole shape before one is placed on the other. The layer 90 10, which constitutes the outer layer of the insole, has U-shaped cuts 14 (Fig. 1) or V-shaped cuts 15 (Fig. 2), preferably made prior to the fastening of the two layers together and forming tabs 16 extending from the inner face of the insole. The width of the margin 18 of the insole between the edge of the insole and the attached end of the adjacent tab is sufficient to allow an outsole and

an upper to be secured together by stitches 95 100

passing through the solid margin 18 of the insole outside of the line of tabs.

In use, the insole is placed upon the bottom of a last 20 with the face having the tabs 16 outermost, the two layers of the insole being coextensive with the last bottom. An upper 5 22 is placed upon the last and lasted over the margin 18 of the insole, successive portions of the upper being secured preferably by a staple 24 driven through the upper and one of the tabs, and clinched on the under side of the tab. The tabs may be raised prior to the lasting operation and if not are readily raised in the stapling operation by the anvil 10 or channel guide of the stapling machine. The machine employed may be of the type disclosed in application Serial No. 721,007, filed June 19, 1924, by George Goddu. In the use of this machine successive portions of the 15 upper are tensioned by a gripper and, while control of the upper is maintained by a staple nozzle, a staple is inserted through a tensioned portion of the upper and one of the tabs 16, the staple being clinched by a channel guide 20 or anvil disposed against the under side of the tab. After the lasting has been effected by securing a tensioned portion of each of the tabs at the two sides of the shoe, the tabs are pressed back into the recesses from which 25 they were cut, leaving the bottom of the insole perfectly flat and substantially unbroken. Filling material may be dispensed with, or at most only enough filler inserted to compensate for the thickness of the margin of 30 the overlasted upper. At the toe and heel the upper may be lasted, for example, on a bed type of lasting machine, and tacks 25 driven through the upper and completely through the insole, their points being clinched by the 35 metal plates with which the toe and heel ends of the last are provided. An outsole is then applied to the shoe, the last removed, and the outsole, upper and insole secured together by through-and-through stitches passing through 40 the margin 18 of the insole outside of the line of the staples.

In Fig. 3 is illustrated an insole comprising two layers 10', 12' of material like that shown in Fig. 1. The novel features of the insole disclosed in Fig. 3 are claimed in a divisional application, Serial No. 370,585, filed June 13, 50 1929. Instead, however, of having tabs 16 formed upon its outer layer 10', the layer 10' of the insole shown in Fig. 3 has a cut along the line 26 extending centrally longitudinally of the sole from the breast line 28 to the tip line 30, together with transverse slits at the tip line and breast line, providing flaps 32 and 34 which may be raised away from the 55 layer 12'. Preferably the layers 10', 12' are attached to each other only along the marginal portions between the tip line and breast line, that is outside of the dotted lines 35 shown in Fig. 3, and such attachment is preferably made by the use of cement, though of

course stitching along the lines 35 may be employed if desired.

The insole of Fig. 3 may be used in substantially the same manner as that shown in Fig. 1. The anvil of a staple lasting machine is passed through the slit 26 beneath the part 32 of the part 34, according to which side of the shoe is being lasted, and in the operation of the machine the upper is drawn over the insole and a staple driven through the upper and one of the portions 32, 34 of the insole, the staple being clinched by the anvil on the under face of the outer layer. An outsole 36 is then applied, as shown in Fig. 4, and secured to the upper and insole by stitches 38.

Having thus described my invention, what I claim as new and desire to secure by Letters Patent of the United States is:

1. An insole comprising a plurality of layers, the outer layer having cuts extending through it and providing portions which may be raised for the insertion of a tool for clinching a fastening driven through the upper and one of said portions. 85

2. An insole comprising a plurality of layers, the outer layer thereof being provided with independent projections consisting of portions displaced from said outer layer and having the thickness of the outer layer, said projections being adapted to have the upper of a shoe secured to them and to be bent back into the recesses from which they were displaced. 90

3. An insole comprising a plurality of layers, the outer layer having cuts extending through it and providing independent tabs formed by displaced portions of said outer layer, said tabs being adapted to have the upper secured to them by independent fastenings and to be bent back into the recesses from which they were displaced. 100

4. An insole comprising a plurality of layers of material, the outer layer thereof being provided with tabs having the thickness of the outer layer and adapted to receive fastenings for securing the upper in lasted position, the attached ends of the tabs being spaced from the edge of the insole to provide a margin for receiving the outsole-attaching stitches. 110

5. An insole for shoes comprising a plurality of layers, the outer layer having U-shaped cuts therethrough to provide tabs to which the upper may be secured. 115

6. An insole for shoes comprising a plurality of layers, the outer layer having tabs at spaced intervals along the margin of the insole and recesses beneath the tabs extending through the outer layer and into which the tabs may be forced after the upper is secured to them. 120

In testimony whereof I have signed my name to this specification.
